DISPLAY SHELF

Seymour Levy, Tarrytown, N. Y.

Application September 23, 1950, Serial No. 12,322

Term of patent 3½ years

(Cl. D80—1)

To all whom it may concern:

Be it known that I, Seymour Levy, a citizen of the United States, residing in Tarrytown, in the county of Westchester, State of New York, have invented a new, original, and ornamental Design for a Display Shelf, of which the following is a specification, reference being had to the accompanying drawing, forming a part thereof, in which:

Fig. 1 is a top plan view of a display shelf, showing my new design;

Fig. 2 is a front elevational view thereof, and

Fig. 3 is a side elevational view thereof.

I claim:

The ornamental design for a display shelf, as shown.

SEYMOUR LEVY.
